UNITED STATES PATENT OFFICE.

ALBERT P. McBRIDE, OF INDEPENDENCE, KANSAS.

EXTRACTING APPLIANCE FOR USE IN OIL OR GAS WELLS.

1,017,305.

Specification of Letters Patent.

Patented Feb. 13, 1912.

Application filed March 29, 1911. Serial No. 618,191.

To all whom it may concern.

Be it known that I, ALBERT P. McBRIDE, a citizen of the United States, residing at Independence, in the county of Montgomery and State of Kansas, have invented certain new and useful Improvements in Extracting Appliances for Use in Oil or Gas Wells, of which the following is a specification.

This invention relates to oil and gas well 10 appliances, and more especially to what may be termed extracting appliances for effecting the removal of detached portions of a pipe or tool from an oil or gas well.

A further object is to produce appliances 15 of the character outlined, of such construction that the customary fishing appliances may be used at the same time to assist in the removal of a detached part of a tool or pipe.

A still further object is to produce ap- 20 pliances of the character mentioned which are of simple, strong, durable and comparatively inexpensive construction.

With these general objects in view and others as hereinafter appear, the invention 25 consists in certain novel and peculiar features of construction and organization as hereinafter described and claimed; and in order that it may be fully understood reference is to be had to the accompanying draw- 30 ing, in which—

Figure 1, shows a part of an oil or gas well with the casing therein and the detached lower end of a boring tool, and also shows in central vertical section appliances 35 for effecting the removal of the detached end of the tool from the well. Fig. 2, is a horizontal section on the line II—II of Fig. 1. Fig. 3, is an enlarged perspective view of the slip or gripper forming a part of 40 such appliances.

Referring now to the drawings, in detail, 1 indicates the customary casing fitting in the boring or well 2, and 3 indicates that portion of the boring which is below the 45 casing, 4 indicating the detached or broken-off end of a boring tool.

5 indicates a cylinder or bowl which is preferably about twelve inches deep and about seven and one-half inches external di- 50 ameter. At its upper end it is internally threaded at 6 and from the lower end of the threaded portion it is of substantially uniform diameter for about half or more than half its length, by preference. From the 55 lower end of the portion of substantially uniform diameter, the walls taper inwardly

to or nearly to their lower ends at 7 and at its lower extremity the cylinder or bowl is beveled to produce the flaring mouth 8 whereby the bowl or cylinder can be more 60 readily centered and slipped over the upper end of the detached or broken-off portion 4 of the tool or other cylindrical object which it is desired to remove from the well. A circular slip or gripper 9 is of size to slip 65 down in the cylinder or bowl until it is en-gaged with the downward tapering portion 7 of the wall, and is externally tapered to correspond with the taper of said portion 7. Internally it is formed with upwardly-dis- 70 posed teeth 10, of the ratchet type in cross section, and at its lower extremity the slip or gripper is beveled at 11 to form a down-wardly flaring mouth for greater conven- 75 ience and despatch in slipping over the up- per end of the detached or broken-off end of the tool. This slip or gripper consists of a plurality of segments 12, each segment hav- 80 ing a V-shaped notch 13 in one end and a corresponding projection 14 at the opposite 85 end so that when the projection of one seg- ment engages the notch of the other, and the slip or gripper is within the cylinder or bowl, it will be impossible for either seg- 90 ment to become disengaged from its com- 95 panion segment, and for convenience in holding the segments together and permit of their swinging toward and from each other, a pivot pin 15 extends downward through one of them and across the notch in the end 90 thereof and through the V-shaped end of the other which engages said notch. Fitting upon the slip or gripper when arranged within the cylinder or bowl is a helical 95 spring 16, and resting upon the upper end of said spring is a ring 17.

When it is desired to remove the de- 100 tached end of a tool or other cylindrical ob- ject from the well, the slip or gripper is dropped into the cylinder or bowl until ar- 105 rested by the lower part of the beveled por- tion 7 thereof. The spring is then dropped into the cylinder or bowl upon the slip or gripper and the ring 17 placed upon the upper end of the spring. The bowl is then 110 secured upon one end of the tube 18, and the spring is placed under compression by the ring through the downward movement im- parted to the latter by the lower end of the tube. The appliance is then lowered into 110 the casing and additional tube sections 18, not shown, are coupled together until the

lower end of the bowl slips over the upper end of the detached or broken-off end 4 of the tool or other cylindrical object, the appliance being then lowered, by preference, an additional two or three feet in which action the slip or gripper will at first be pressed upward by the upper end of the part 4, because when fully contracted its bore is of slightly less diameter than that of such part 4. The spring yields under such upward movement of the slip or gripper until the latter expands sufficiently to slip over the upper end of the tool. When the tool or appliance is lowered the desired distance the spring reexpands and forces the slip or gripper downward until the tapered portion 7 of the cylinder or bowl clamps the segments 12 firmly upon the tool or part 4. When thus arranged a screw jack, not shown, is employed to exert an upward pull upon the topmost tube 18, this upward pull being applied by the slip or gripper on the tool or part 4, there being no slippage as the wedge relation between the slip or gripper and the cylinder or bowl increases the grip of the former upon part 4, proportionately as the pull on the screw jack increases.

Under ordinary conditions the operation described results in loosening and raising the tool or part 4. In the event that it is impossible to effect the removal of the tool or part in the manner and by the means described, it is possible to go down through the line of tube 18, with what is technically known as a set of fishing tools and a cable, not shown, because of common and well known construction and use. By means of these fishing tools an upward jerking action can be applied on part 4 without interfering with the steady upward pull on said part by the slip or gripper, because the part 4 if suddenly loosened under the upward jarring action, is free to slide upward as the slip or gripper will instantly move upward and outward and release it, the spring yielding and then reacting suddenly so that the slip or gripper shall be ready to reengage and hold the part 4 as the upward movement imparted to the same by the fishing tools ends. After the part is thus loosened the fishing tools may be removed and the appliances described and shown, relied upon to lift the part out of the well, the tube sections 18 being uncoupled as they successively emerge from the well, as will be readily understood.

From the above description it will be apparent that I have produced extracting appliances for use in oil or gas wells, possessing the features of advantage enumerated as desirable, and while I have illustrated and described the preferred embodiment of the invention, I wish it to be understood that I do not desire to be restricted to the exact details of construction shown and de-

scribed, as obvious modifications will suggest themselves to one skilled in the art.

I claim:—

1. An extracting appliance, comprising a cylinder having a portion of downwardly-decreasing internal diameter, a circular slip or gripper to fit within the cylinder and of downwardly-decreasing external diameter to engage said portion of the cylinder of downwardly-decreasing internal diameter; said slip or gripper being formed internally with teeth and consisting of a plurality of segments pivotally connected together. 70

2. An extracting appliance, comprising a cylinder having a portion of downwardly-decreasing internal diameter, a circular slip or gripper to fit within the cylinder and of downwardly-decreasing external diameter to engage said portion of the cylinder of downwardly-decreasing internal diameter; 80 said slip or gripper being formed internally with teeth and consisting of a plurality of segments fitting endwise together and interlocked at such ends as regards independent vertical movement of the segments. 85

3. An extracting appliance, comprising a cylinder, having a portion of downwardly-decreasing internal diameter, a circular slip or gripper to fit within the cylinder and of downwardly-decreasing external diameter to engage said portion of the cylinder of downwardly-decreasing internal diameter; 95 said slip or gripper being formed internally with teeth, and consisting of a plurality of segments fitting endwise together and interlocked at such ends as regards independent vertical movement of the segments; and a vertical pivot pin extending downward through abutting ends of the sections. 100

4. An extracting appliance, comprising a cylinder having a portion of downwardly-decreasing internal diameter, a circular slip or gripper to fit within the cylinder and of downwardly-decreasing external diameter to engage said portion of the cylinder of downwardly-decreasing internal diameter; 110 said slip or gripper being formed internally with teeth and consisting of a plurality of segments pivotally connected together, a spring fitting in the cylinder upon the upper or enlarged end of the slip or gripper, a ring fitting in the cylinder upon the upper end of the spring, and a tube secured in the upper end of the cylinder and overlying the ring to prevent upward movement 115 thereof. 120

5. An extracting appliance, comprising a cylinder, having a portion of downwardly-decreasing internal diameter, and a flaring mouth at its lower end, a circular slip or gripper to fit within the cylinder and of downwardly-decreasing external diameter to engage said portion of the cylinder of downwardly-decreasing internal diameter; 125 said slip or gripper being formed in- 130

ternally with teeth and consisting of a plurality of segments pivotally connected together, and beveled at their lower ends to provide a downwardly flaring mouth, and a tube secured at its lower end to the upper end of the cylinder.

6. A circular slip or gripper of downwardly-tapering external diameter and provided internally with upwardly and inwardly disposed teeth, and consisting of a plurality of segments each terminating at one end in a V-shaped projection and at the other in a V-shaped notch, the notch of one

segment receiving the projection of the other, and a pivot pin extending down 15 through the notched end of one segment and the V-shaped end of the other to permit the segments to swing toward or from each other.

In testimony whereof I affix my signature, in the presence of two witnesses.
